CLAIM

The ornamental design for a travel trailer front portion, as shown and described.

DESCRIPTION

FIG. 1 shows a left side view of the design of the present invention, the right side being a mirror image thereof; and, FIG. 2 shows a front view of the embodiment of FIG. 1, the back, top, and bottom views forming no portion of the claimed invention.

The dashed lines illustrate features of the travel trailer which are not part of the claimed invention.
